UNBALANCED TO BALANCED LINE
TRANSFORMERPaul D. Coleman, Dayton, Ohio, assignor to The
United States of America as represented by the
Secretary of War

Application January 3, 1945, Serial No. 571,191

5 Claims. (Cl. 178—44)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to transformers and more particularly to transformers for making a transformation from a 50 ohm unbalanced line to a 100 ohm balanced line.

Among the main objects of the present invention are to overcome the disadvantages of the excessively large and weighty prior art transformers as well as other disadvantages, and produce a simple, efficient, light weight, compact transformer of the type stated which may be quickly made from readily obtainable materials, with relatively few operations and corresponding comparatively low cost.

In order to more clearly disclose the construction, operation and use of the invention, reference should be had to the accompanying drawings forming part of the present application.

Throughout the several figures of the drawings like reference characters designate the same parts in the different views.

In the drawings:

Fig. 1 is a side elevation, with case indicated in dotted lines;

Fig. 2 is an enlarged cross section of one coaxial cable;

Fig. 3 is a like view of the combined cable, referred to as composite;

Fig. 4 is an enlarged, longitudinal cross section, diagrammatically, of the connections between cables.

The unbalanced line is of 50 ohm coaxial cable, while the balanced line consists of two 50 ohm coaxial cables.

The invention comprises a special coaxial cable specially combined to provide another special cable which I refer to or call a composite cable, being elements of two such coaxial cables combined into one cable.

The coaxial cable, shown in enlarged cross section in Figure 2, comprises the center conductor 1, dielectric 2, conducting enclosing or inner braid 3, dielectric layer 4 and the outer braid or conductor 5. By providing the outer conducting braid 5 which is absent from the usual coaxial cable, the coaxial cable of this invention is, actually, a cable within a cable, i. e. conductors 1 and 3 may be connected, or conductors 3 and 5 may be connected.

Two of these special coaxial cables are then combined to provide the composite cable of this

2

invention, shown in cross section in Figure 3. In so combining the two cables, the outer braid conductor 5 of each is removed throughout the length to be combined. They are laid parallel with the dielectrics 4 contacting. In this position a conductor braid 6 is woven or otherwise wrapped about the assembled coaxial cables. This assemblage is approximately elliptical in lateral cross section, the short axis having a length substantially that of the diameter of the component coaxial cable while the long axis is of substantially twice that length. This assemblage, as will be clear on reference to Fig. 3 comprises five conductors, i. e. outer conductor 6, the two inner braid conductors 3 and the two center conductors 1.

Reference is now made to Fig. 4. In Fig. 4, the left-hand composite cable is designated A, A', while the pair of coaxial cables on the right-hand is designated B, B'. This view shows the total length, in cross-section, of the combined cables between connectors 9 and 10, the center of this view being the point where clip 11 of Fig. 1 is applied. Terminal 9 of Fig. 1 is connected to the left-hand end of the unbalanced 50 ohm cable line formed by the center conductor 1 and the inner braid 3 of coaxial cable A of the composite cable A, A'. Cable A' is shorted at the left end thereof and soldered to the inner braid 3 of cable A. Thereafter, the connection of A to A' may be traced through a line that is one-quarter of a wavelength at the mean operating frequency range, and is formed by conductors 1 and 3 of cable A, as indicated. The center conductor 1 of the coaxial cable A is deflected near the center of Fig. 4, cut, and soldered to the inner braid conductor 3 of coaxial cable A'. Inner braid 3 of cable A' continues as the inner braid 3 of coaxial cable B'. The inner braid 3 of coaxial cable A is connected to the inner braid 3 of coaxial cable B. Cables B and B' are respectively connected to connectors 10 of Fig. 1. Thus, the inner braid conductors 3 of coaxial sections B and B' become the center conductors of a 100 ohm balanced line, the outer conductors being the outer braids 5. These coaxial sections B and B' are, as indicated, of the same electrical length as the special composite cable hereinabove described. In Fig. 4, conductors 5 and 6 are shown as being grounded. These conductors are actually grounded near their centers through the clip 11, shown in Fig. 1.

These special, flexible coaxial cables combined as described into the special composite cable of this invention, as a unit, are coiled and mounted

as shown in Fig. 1. So mounted, the assemblage constitutes a complete transformer unit readily enclosed within a suitable protecting housing or case 7.

The mounting plate or base 8 may be made in any suitable and well known manner, as by stamping, for instance. It is, of course, provided with the input connector 9 for the unbalanced end of the line and a pair of connectors 10 for the balanced ends, all as will be readily understood. Preferably, base 8 is provided with short flanges which act as guides to facilitate inserting the unit into its case and withdrawing it from its case. Preferably a suitable clip 11 is provided at about longitudinal center of the plate and adapted to extend across or bridge the cable, in coiled form.

The cables may be held in coiled form either by wrapping with cord, tape, or the like or by using one or more readily applied clips.

The flexibility of this type of cable permits ready compact coiling and by arranging the component coaxial coils as stated the short diameter of the ellipse of that composite portion is approximately aligned with the diameter of the coil. This approximately maintains the same flexibility in the composite portion as exists in the separate coaxial sections. Cables so made and assembled may be quickly, easily and compactly coiled.

As will appear on reference to Fig. 4 the center conductor 1 of the component coaxial cable A' and of cable B' is unused or idle, throughout. These components could be made without it. However, it is simpler to make all components the same and leave that conductor unused than it is to make one set of coaxial cables with a center conductor and another set without. From the same view, it will also be obvious that the center conductor 1 of terminal section B is dead or idle because it has been cut near the point of deflection of conductor 1 of cable A where it is soldered to the inner braid conductor 3 of the component A'. Thus cable A of the two components A and B must have a central conductor 1 whereas the remaining one need not have a central conductor.

It is thought that the construction, operation and use of the invention will be clear from the preceding detailed description.

Having thus described my invention what I claim and desire to protect by Letters Patent is:

1. An unbalanced to balanced line transformer, comprising a composite unbalanced cable including first and second flexible parallel cables each

having a center and a separate enclosing outer conductor, said cables being compositely enclosed in an outer conductor of approximately one-quarter of a wavelength, one end of said second cable being shorted at one end of said composite conductor to the separate outer conductor of said first cable, and the center conductor of said first cable being shorted to the separate outer conductor of said second cable at the other end of said composite conductor, and third and fourth flexible balanced cables, each having center, inner, and outer conductors of approximately one-quarter of a wavelength, the inner conductors of said third and fourth cables being respectively connected at one end to the separate outer conductors of said first and second cables at the other end of said composite conductor, and the center conductor at said one end of said fourth cable being connected to the center conductor of said second cable at the other end thereof, said cables being arranged to form a coil, said one end of said first cable being adapted to receive an unbalanced input and the other ends of said third and fourth cables being adapted to provide the balanced output therefrom.

2. The transformer of claim 1, further including means for maintaining said cables in the form of a coil.

3. The transformer of claim 2, wherein said means comprises clip means connected to the other ends of said first and second cables, and to the one ends of said third and fourth cables.

4. The transformer of claim 1, further including a housing for said cables, said housing having an unbalanced input connector coupled to the one end of said first cable and two balanced output connectors, each respectively coupled to the other ends of said third and fourth cables.

5. The transformer of claim 4, further including clip means connected to the other ends of said first and second cables and to the one ends of said third and fourth cables, for maintaining said cables in coil form.

PAUL D. COLEMAN.
